REINFORCING-BAR.

1,282,616.

Specification of Letters Patent. Patented Oct. 22, 1918.

Application filed April 22, 1916. Serial No. 230,117.

To all whom it may concern:

Be it known that I, CHARLES F. MURRAY, a citizen of the United States, and resident of Evanston, in the county of Cook and State of Illinois, have invented certain new and useful Improvements in Reinforcing-Bars, of which the following is a specification.

My invention relates to reinforcing bars for concrete and more particularly to a bar having a novel rib construction.

It is becoming the practice among engineers in their specifications for reinforcing bars to require that the same shall be provided with transverse ribs of substantial size, the use of diagonally disposed ribs of all sorts not being favored. In view, however, of the peculiarities of the process of rolling and of the necessity for great speed of production, it has heretofore been found impossible to roll bars having transverse ribs without distorting the ribs and seriously affecting the efficiency thereof. Not only is the efficiency of the rib reduced by such distortion but an equally serious objection is made thereto because of the loss in power due to interference between the bar and the rolls and the consequent rapid wear of the rolls. The cost of producing rolls is high and the necessity for constant renewal of the rolls adds materially to the cost of production of the bar. Furthermore, the loss in power due to the frictional resistance resulting from the distortion of the ribs is great and may amount to 10 to 20% of the total power.

An object of this invention is to so design a transverse rib that there will be no distortion thereof in rolling and consequently less wear on the rolls and less loss of power in rolling. The rib is designed to meet the following rolling conditions; it will be understood that reinforcing members such as commonly used today are formed by passing a heated bar between a pair of rolls, one-half of the pass being contained in each roll. The bar which is fed into the rolls is of anywhere from 25 to 35% larger cross sectional area than that of the bar which issues from the pass. This is necessary in order that there will be sufficient material to fill the grooves in the roll and form the ribs on the bar. It will be understood also that the grooves which serve to form the ribs on the

bar must be arranged radially of the roll and consequently that the grooves are in line with the ribs formed on the bar only at one point; that is, at a point coincident with a line intersecting the axes of the two rolls; furthermore that the angularity between the groove and the rib formed thereby increases with the angularity of the roll due to the tangential movement of the bar. The difficulties arising from this fact are increased due to the fact that the reduction in size of the bar implies and necessitates a corresponding elongation of the bar; that is, theoretically if there is a 25% reduction on the bar in the rolls, the bar should issue from the rolls 25% faster than it enters and correspondingly faster than the peripheral speed of the rolls. It has been found that the elongation of the formed bar as it emerges from the roll is not proportioned to the amount of reduction, but is approximately 4 to 5% in excess of the periphery of the rolls at approximately 30% reduction. The effect of the increasing angularity between the groove in the roll and the rib on the bar and the increase in speed of travel of the rib over the peripheral speed of the roll results in wiping off or distorting the portion of the rib which is not yet freed from the roll. A rib constructed as described herein will not be distorted and will be freed from the roll without conflict therewith.

The difficulties in designing a rib which will not be distorted by the roll are further increased when the surface by which the rib is formed is disposed at an angle of approximately 45° to the axis of rotation of the roll. This has the effect upon relative movement between the bar and the roll of moving a point within the groove on the roll in a path which is inclined with relation to both the longitudinal and transverse axes of the rib which has been formed in the groove. Thus it follows that the rib in order to be freed from the roll without distortion and friction loss should be inclined on the side which would naturally be distorted, the inclination being made to correspond to the path of movement of the point referred to on the rib. Thus it is found that the rib should be provided on its delivery side with a double incline.

The foregoing description will

understood by reference to the accompanying drawings, wherein:

Figure 1 is a transverse sectional view through a pair of rolls in which a bar constructed in accordance with my invention is being formed;

Fig. 2 is a sectional view on the line 2—2 of Fig. 1;

Fig. 3 is an irregular sectional view on the line 3—3 of Fig. 1;

Figs. 4, 5, 6 and 7 are views somewhat diagrammatical in form but in effect taken on the line x—x of Fig. 2, the bar being shown in full lines and the different positions of the groove in the roll with relation to the rib being shown in dotted lines;

Figs. 8, 9, 10 and 11 are views taken on the lines 8—8, 9—9, 10—10 and 11—11 of Figs. 4, 5, 6 and 7 respectively.

20 The bar is shown as being generally rectangular in outline although it may be made round if desired. It is preferably provided with a main or body portion 10, having four diametrically opposed longitudinal 25 extending corner ribs 11. The longitudinal ribs are joined by directly transverse ribs 12, one face 13, of which is substantially perpendicular to the longitudinal axis of the bar while the other face 14, is inclined both in relation to the longitudinal axis of the rib and the transverse axis thereof. From a strict technical standpoint, the surface of the rib should be cycloidal, but from a practical standpoint this is immaterial and unimportant. At one end the rib is substantially complete; that is, it has a vertical face and is of the full width. At its top the rib is lessened in thickness on substantially a straight line to its opposite 40 extremity. The width of the rib at its top is immaterial and at the point of greatest inclination it may be relatively thin if desired. Inasmuch as the angle at the point of greatest inclination would never be more 45 than 45°, the strength of the rib will be sufficient, particularly in view of the fact that it is anchored to the longitudinal rib 11, at that point.

It will be noted that the bar is formed 50 by passing the same between the rolls 15, 16, each of which has one-half of the pass formed therein. In effect therefore, one-half of the bar is formed in each roll and as the ribs 12, are located at an angle 45° 55 to the axis of rotation of the rolls, the difficulty in freeing the ribs from the roll will be apparent. The motion of the parts from the point at which the formation of the rib is completed to that at which the rib is 60 entirely free from the roll, are shown in Figs. 4 to 11 inclusive. In Figs. 4 and 8 the rib and groove are coincident, the views being taken at the point where the line

through the longitudinal axes of the ribs is parallel to the line through the axes of the rolls. In Figs. 5 and 9, however, it will be seen that the groove, indicated by the dotted line 17, has shifted both longitudinally and transversely of the rib and has moved away from the rib to the extent indicated by the space 18, in Fig. 9. This peculiar movement continues, as shown in Figs. 6 and 10, until at the point shown in Figs. 7 and 11, the roll is free from the rib.

The point 19, of the roll, which is a point on the extreme periphery, remains substantially in contact with the rib until the roll has moved entirely out of contact with the bar, and as this point on the roll has considerably greater peripheral speed than the inner point, due to its greater distance from the axis of the roll, it would contact with the rib and distort it were it not for the fact that the bar moves substantially 4% faster than the peripheral speed of the roll. Because of this there is no distortion of the bar by the angular movement of that point of the roll.

The foregoing description has reference solely to the method of forming the roll in order to produce a bar having ribs such as described and is thought to be necessary in order to enable those skilled in the art to produce such a bar.

I claim:

1. A reinforcing member for concrete, comprising a bar having spaced, transverse ribs thereon, said ribs having one face which is substantially perpendicular to the face of the bar, and one face of which is inclined longitudinally and vertically, substantially as described.

2. A bar having transverse ribs, one face of which is perpendicular to the bar and the other face is inclined longitudinally and vertically, the double inclination being such that the ribs will be freed from the rolls without distortion, substantially as described.

3. A reinforcing member for concrete, comprising a bar having spaced, transversely extending ribs thereon, said ribs having one face which is substantially perpendicular to the face of the bar whereby to provide an extended straight bonding surface, and the opposite face of said ribs being inclined longitudinally and vertically, whereby the forming rolls will be freed from the ribs without distortion of the latter, substantially as described.

Signed at Chicago, Ill., this 20th day of April, 1918.

CHARLES F. MURRAY.

Witness:

T. D. BUTLER.
